UNITED STATES PATENT OFFICE.

PHILIP K. MUSSELMAN, OF DUBLIN, PENNSYLVANIA.

CARRIER.

1,084,951.

Specification of Letters Patent.

Patented Jan. 20, 1914.

Application filed March 11, 1913. Serial No. 753,487.

To all whom it may concern:

Be it known that I, PHILIP K. MUSSELMAN, a citizen of the United States, residing at Dublin, in the county of Bucks and State of Pennsylvania, have invented certain new and useful Improvements in Carriers, of which the following is a specification.

My invention relates to improvements in carriers, the object of the invention being to provide a carrier which is designed especially for carrying manure from a barn and dumping the same automatically when the carrier reaches a pre-determined point.

A further object is to provide an improved support for the cable upon which the carrier runs, said support secured to the barn and adapted to be raised and lowered so as to raise and lower the cable, so that the latter may be positioned out of the way when not in use.

A further object is to provide an improved carrier which is of extremely simple construction, strong and durable in use.

With these and other objects in view, the invention consists in certain novel features of construction and combinations and arrangements of parts as will be more fully hereinafter described and pointed out in the claims.

30 In the accompanying drawings: Figure 1 is a view illustrating my improvements in connection with a barn: Fig. 2 is an enlarged view in side elevation of the carrier. Fig. 3 is an end view of the carrier. Fig. 4 is a view partly in longitudinal section and partly in elevation illustrating the means for operating the receptacle holding latch pin. Fig. 5 is a view in section on an enlarged scale through one of the carrier supporting brackets. Fig. 6 is a plan view on an enlarged scale illustrating the cable supporting device, and Fig. 7 is a view in elevation showing the device in position on a barn and its supporting means.

45 1 represents an ordinary barn through the door 2 of which my improved carrier 3 is adapted to run upon a cable 4^a and carry manure from the barn to any suitable dumping point indicated at 6^a, and means shown at 7^a are provided to raise and lower the cable 4^a and compel the car to run by gravity in both directions.

The carrier 3 comprises an open top receptacle 4 having trunnions 5 at its ends mounted to turn in bars 6 and 7 respectively, the former preferably flat as indicated, and

the latter cylindrical to embody the maximum of strength. These bars 6 and 7 at their upper ends are secured to a horizontal bar 8, the latter being strengthened intermediate its ends by a truss 9.

60 Rods 10 connect the bars 8 with the bars 6 and 7 and are strengthened by struts 11 between their ends. The truss 9 above referred to is also provided centrally with a strut 11 and hence at this central point, the maximum of strength is had.

65 The receptacle 4, at one end, is provided with a horizontal curved plate 12, which latter has an opening 13 therein to receive a latch pin 14. The latch pin 14 extends through an opening 15 in the bar 6, and through an opening 17 in a strip 18 secured to bar 6.

A coiled spring 16 is positioned around 70 pin 14 and bears at one end against the bar 6. The other end of this spring bears against a cross pin 19 in latch pin 14 so as to press the latch pin into the opening 13 in plate 12 and hold the receptacle against 75 tilting movement.

80 The receptacle is over-balanced slightly at one side, so that when the latch pin is withdrawn, it will fall of its own weight to dump as indicated in dotted lines in Fig. 8. 85 The outer end of latch pin 14 has a transverse journal 20 on which rollers 21 are mounted to turn.

A wedge block 22 is secured to a sliding bar 23, and is provided with a longitudinal 90 slot 24 to receive the pin 14, yet present the beveled or inclined surface of the block to the rollers 21, so that when the block 22 is moved downwardly, it will draw the latch pin out of engagement with strip 12. The 95 upper end of bar 23 is bent at right angles forming a tongue 25. A vertical rod 26 having a screw-threaded lower end is screwed through a threaded opening in the tongue 25 to connect the rod and the 100 tongue, and a nut 27 is screwed onto the lower end of the rod to hold the latter against independent movement. The rod 26 projects through the bar 8, and is provided with a cam plate 28 on its upper end. A coiled spring 29 is positioned around rod 26 between bar 8 and plate 28, and holds the rod and the parts with which it is connected in their highest position.

110 A cam 30 is located at a suitable point on cable 4^a, and when the carrier reaches this point, the cam 30 operates to depress plate

28 and cause the latch pin to be withdrawn as will be readily understood. I may provide various forms of cam 30, but the one illustrated, and which is a preferred one, 5 comprises simply a piece of wire bent at its ends around the cable 4, and having a strut 31 between its ends to hold it in cam formation.

Brackets 32 are pivotally connected to bar 10 8 by bolts 33 and nuts 34. These brackets 32 each comprise a single bar which is bent between its ends forming a relatively long arm 35, and a relatively short arm 36. Through the long arm 35, a journal bolt 37 15 is projected, and secured in place by a nut 38. A grooved wheel 39 is mounted upon the journal bolt 37 and is adapted to run on the cable 4^a. To prevent the wheel from jumping off the cable, a guard 40 is provided and comprises a section of wire which 20 is bent as indicated clearly in Fig. 5 forming a journal 41 extending through openings in the arms 35 and 36 respectively, and at one end bent up beside the pulley as 25 clearly shown. The opposite end of the journal 41 has a crank arm 42 thereon which is connected by a coiled spring 43 with a fixed pin 44 on arm 35, so that the guard 40 is normally maintained in a vertical position, yet it may swing out of the way to 30 allow the device to pass a cable support.

In Figs. 6 and 7, I illustrate on an enlarged scale, my improved cable support 45 which permits the cable to pass through the 35 door 2 of the barn, and then in any desired direction without bending the cable at an angle. The support 45 comprises a frame consisting of a plurality of radially positioned bars 46 connected by transverse bars 40 47. The central bar of the frame is longer than the others, and is connected by a suitable hinge connection 48 with the barn, so that the device may be raised and lowered. The outer ends of all of the bars 46 are 45 provided with cable clamps 49, so that the cable 4^a is held therein, yet the wheels 39 are permitted to pass over the clamps, because the latter are of thin sheet metal and would not derail the device. This support, when in 50 normal position, lies in front of the door as indicated in Figs. 1 and 7. To support it in this position and elevate the same out of the way when not in use, I provide an adjustable hanger as shown most clearly in 55 Fig. 7. This hanger comprises two bars 50 and 51 which are connected by straps 52, so that they slide one beside the other. A cam lever 53 is connected to bar 51, and is connected by links 54 with the bar 50. The upper 60 end of bar 51 is secured to a fixed support 55, so that when the lever 53 is raised and lowered, the support 45 will be raised and lowered. When raised, it will hold the cable out of the door-way, so that the door 65 may be shut.

With my improvements, the receptacle may be loaded within the barn, and then caused to run by gravity to the point of dump where the latch pin 14 will be withdrawn through the medium of the mechanism above described, and the receptacle automatically dump. The car may be also returned by gravity as will be readily understood, and while I have indicated, a simple device for causing the cable to incline in both directions, it is to be understood that the invention is not limited in this particular.

Various slight changes might be made in the general form and arrangement of parts 20 described without departing from my invention, and hence I do not limit myself to the precise details set forth, but consider myself at liberty to make such changes and alterations as fairly fall within the spirit 35 and scope of the appended claims.

Having thus described my invention, what I claim as new and desire to secure by Letters Patent is:

1. A carrier of the character described, 90 comprising a frame, wheels supporting the frame, a receptacle having trunnions at its ends supported in said frame, a plate secured to one end of the receptacle and inclining at both ends toward the ends of the receptacle, said plate having an opening therein, a spring-pressed latch pin on the frame normally projecting into said opening and holding the receptacle in an upright position, a cross pin connected to the latch pin, 100 a vertically movable wedge block engaging between the frame and said cross pin, and means for moving the wedge in a direction to move the latch pin out of the opening in the plate, substantially as described. 105

2. A carrier of the character described, comprising a frame, wheels supporting the frame, a receptacle having trunnions at its ends supported in said frame, a plate secured to one end of the receptacle and inclining at both ends toward the ends of the receptacle, said plate having an opening therein, a spring-pressed latch pin on the frame normally projecting into said opening and holding the receptacle in an upright position, a cross pin connected to the latch pin, rollers on said cross pin, a vertically movable wedge having a slot therein straddling the latch pin and positioned between the rollers and the frame, and means for moving said wedge, substantially as described. 110 115

3. A carrier of the character described, comprising a frame, wheels supporting the frame, a receptacle having trunnions at its ends supported in said frame, a plate secured to one end of the receptacle and inclining at both ends toward the ends of the receptacle, said plate having an opening therein, a spring-pressed latch pin on the 125 130

frame normally projecting into said opening and holding the receptacle in an upright position, a cross pin connected to the latch pin, a vertically movable wedge block engaging between the frame and said cross pin, a spring exerting pressure on the wedge to normally hold it out of operative engagement with the latch pin, and a cam plate adapted to engage a fixed part, whereby the wedge is moved in a direction to release the latch pin from engagement with the plate, substantially as described.

4. A carrier of the character described, comprising a frame, wheels supporting the frame, a receptacle having trunnions at its ends supported in said frame, a plate secured to one end of the receptacle and inclining at both ends toward the ends of the receptacle, said plate having an opening therein, a spring-pressed latch pin on the frame normally projecting into said opening and holding the receptacle in an upright position, a cross pin connected to the latch pin, rollers on said cross pin, a vertically movable wedge having a slot therein straddling the latch pin and positioned between the rollers and the frame, a spring exerting

pressure on the wedge to normally hold it out of operative engagement with the latch pin, and a cam plate adapted to engage a fixed part, whereby the wedge is moved in a direction to release the latch pin from engagement with the plate, substantially as described.

5. A carrier of the character described, comprising a wheel supported frame, a receptacle pivotally mounted in the frame, a curved plate secured to one end of the receptacle and having an opening therein, a spring-pressed latch pin in the frame normally positioned in said opening, a cross pin at the free end of the latch pin, a slotted wedge block straddling the latch pin and engaging the cross pin, and a spring-pressed cam plate connected with said wedge and normally holding the same in inoperative position, substantially as described.

In testimony whereof I have signed my name to this specification in the presence of two subscribing witnesses.

PHILIP K. MUSSELMAN.
